UNITED STATES PATENT OFFICE

CHARLES R. CRANE, 2D, OF CHICAGO, ILLINOIS, ASSIGNOR TO CRANE CO., OF CHICAGO, ILLINOIS, A CORPORATION OF ILLINOIS

ENAMELED IRON PLUMBING FIXTURE

Application filed May 8, 1929. Serial No. 361,272.

This invention pertains to enamel coated metal plumbing fixtures such as basins, tubs and the like, although in some aspects it is of broader application, and more particularly relates to a construction for edge portions of such fixtures etc. whereby the enamel will "take" along such edge portions, adhere thereto and cover the same uniformly.

It has been found practically impossible to make a vitreous enamel coating adhere to and cover the edges of enameled ware so that a uniform coating extending to or covering the edge resulted. No matter how clean the surfaces of the metal to which the enamel is applied, the enamel "draws" or "creeps" back from the edge at different places or thins out to such an extent that the metal is not thoroughly or uniformly covered along such edge. Various theories have been advanced as to the reasons for this action and many attempts have been made to avoid the difficulty, but so far as I am aware, no successful solution has been provided heretofore.

This condition is decidedly objectionable in the case of enameled iron plumbing ware or fixtures, where it is desired not only to have the metal properly covered for protection, but also to present a more sightly and pleasing appearance originally as well as after 30 years of use. There are therefore both economic and æsthetic disadvantages in such articles where the metal of the edges is not covered or uniformly covered by the vitreous enamel coating.

The unsatisfactory features of enameled ware plumbing fixtures as above related are probably nowhere more objectionable than when they occur about the marginal edges of an overflow or waste orifice or the like in an enameled ware basin or tub, if such overflow or waste orifice be not covered by a screen or strainer or escutcheon plate. At such places it is particularly difficult to get the enamel to adhere properly. If the enamel is thin about the edges of the openings through which the faucets and waste control mechanisms project, it usually does not matter so much from the standpoint of appearances because escutcheon plates or the like are ordinarily designed to cover such defects.

With my invention or discovery I am enabled to get the enamel to cover the edges of the metal article uniformly and completely so that the metal does not show through or come in direct contact with corrosive influences therealong. This may be said to be one of the important objects of the invention.

Another object of the invention is to provide a novel type of construction for the formation of an overflow orifice or passage, particularly suitable for wash bowls or basins, whereby the difficulties of enameling previously encountered are entirely overcome, the enamel adhering uniformly and being of the desired and proper thickness.

Many further objects including the provision of an overflow orifice or passage construction substantially concealed from the view of the ordinary observer, as well as advantages and uses of the invention, will be or should become readily appreciated and understood after reading the following description and claim, and after viewing the drawings, in which:

Fig. 1 is a sectional elevation taken from front to rear of a lavatory or the like, showing the invention applied to the overflow orifice or passageway.

Fig. 2 is a fragmentary front elevation of the rear wall including the overflow passage of the lavatory of Fig. 1; said view being on an enlarged scale, and

Fig. 3 is a sectional elevation on the scale of Fig. 2 taken substantially along the line 3-3 of Fig. 2.

For the sake of convenience and simplicity the invention has been illustrated as applied to a lavatory or wash basin which will be designated as a whole by the reference character 2. This plumbing fixture is preferably cast iron and made as a single casting. It includes a depressed portion or basin proper 3, a rim 4 and a depending skirt 5 extending about the entire perimeter of the bowl. The bottom wall of the bowl is provided with an outlet orifice 6 and the rear wall 7 is provided with an outlet orifice or passage 8, while a wall 9 provides a space through which water from the outlet and overflow orifices may flow to a waste pipe 100.

connection orifice 11 and through which a waste control mechanism of the "pop-up" type may be disposed. The rim portion 4 at the rear will be provided with one or more faucet and pipe connection openings 12 and an opening 13 through which the waste control mechanism passes.

If sharp corners on the surfaces about or to which the enamel is to be applied are eliminated and the surfaces rounded thereat, the enamel will adhere and adhere with uniform thickness and extent and will not "creep" or "draw" as has heretofore been the case. Therefore, wherever it is desired to have the vitreous enamel extend to or about an edge, the edge is rounded as illustrated at 14, 15, 16, 17 and 18. Fig. 3 more clearly illustrates the manner in which the edges are rounded and how the enamel 19 adheres to and covers the same, whereas if the edges were sharp, the enamel would "draw" or "creep", or would be so thin in spots as to provide an unsightly appearance and to permit corrosion to take place.

The rear upstanding wall 7 is provided with a rearwardly and upwardly extending portion 21 and merges at its sides with rearwardly extending portions 22, thereby providing a lip which tends to cause the water flowing thereover to pour into the space between the walls 7 and 9 without contacting with the unenameled rear side of the wall 7. The portion 21 gradually curves into and merges with the wall 7 as shown at 23 and the side walls 22 likewise gradually curve into and merge with the wall 7 as shown as 24 while the corners 25 are similarly rounded or filleted. This gradual merging or rounding of the edges and corners at and about the outlet orifice together with the rounded edges 17 and 18 and the inclined lip wall 21 enables the enamel to be applied to the surfaces defining the overflow orifice and to "take" thereto uniformly and completely, and difficulties heretofore encountered in applying enamel properly about such orifices are entirely obviated.

The wall forming the margin along the top of the overflow orifice or passage preferably lies in the plane of the wall 7 as a whole, but is bevelled off as shown at 26 to maintain the passageway of the desired width throughout. The arrangement of the walls about and forming the overflow passage also give a neat appearance to the article while the fact that the overflow orifice is practically concealed from the view of a casual observer of itself lends to the attractiveness of the fixture.

While the invention has been illustrated and described in connection with the plumbing fixture and in a preferred embodiment, it will be appreciated that it is of broader scope. Therefore, I do not desire to be

limited except by the spirit of the invention and the scope of the appended claim.

I claim:

In a plumbing fixture of the character described, a receptacle formed of cast metal having a coating of vitreous enamel thereon, said receptacle having an upstanding wall provided with an elongated overflow orifice, said orifice being provided with an elongated horizontally extending upper edge, portions of the wall at the sides and bottom of the orifice extending outwardly and upwardly of the receptacle and providing an elongated horizontally extending lip substantially the same thickness as the wall thickness and terminating in a lower elongated horizontally extending edge disposed rearwardly of said upper edge of the orifice whereby the orifice is substantially concealed from the view of a casual observer, said coating of vitreous enamel extending over the interior side of said receptacle including said lip.

In witness of the foregoing I affix my signature.

CHARLES R. CRANE, II.
